(57) **CLAIM**

The ornamental design for a consumer paint sprayer with overhead hopper, as shown and described.

DESCRIPTION

FIG. 1 is a perspective view of a consumer paint sprayer with overhead hopper of the present invention.

FIG. 2 is a front elevation view of the paint sprayer of FIG. 1.

FIG. 3 is a rear elevation view of the paint sprayer of FIG. 1.

FIG. 4 is a left side elevation view of the paint sprayer of FIG. 1.

FIG. 5 is a right side elevation view of the paint sprayer of FIG. 1.

FIG. 6 is a top plan view of the paint sprayer of FIG. 1; and, FIG. 7 is a bottom plan view of the paint sprayer of FIG. 1.

The broken lines in FIG. 1 illustrate the appearance of the handle in an extended position.
